Inventor:

B. F. Farrar.

United States Patent Office.

BENJAMIN F. FARRAR, OF SPRINGFIELD, MASSACHUSETTS, ASSIGNOR
TO HIMSELF AND D. B. WESSON, OF SAME PLACE.

Letters Patent No. 66,136, dated June 25, 1867.

IMPROVEMENT IN SAFETY RAILROAD-SWITCH.

The Schedule referred to in these Letters Patent and making part of the same.

TO ALL WHOM IT MAY CONCERN:

Be it known that I, BENJAMIN F. FARRAR, of Springfield, Hampden county, Commonwealth of Massachusetts, have invented a new and useful Safety-Switch for railroad tracks; and I do hereby declare that the following is a full and exact description thereof, reference being had to the accompanying drawings, and to the letters of reference marked thereon. In these drawings—

Figure 1 represents a plan view of my switch, and

Figure 2 an end view of the same.

My invention consists of a railroad switch so arranged as to render it impossible for a train to run off the track by means of its displacement, the cars themselves forcing the switch into position until they pass, when the switch resumes its original position.

In fig. 1 of the drawings, the rails marked A form the straight track, and those marked B the branch. The switch is formed of two parallel rails, C and D, hinged at X, and are operated by the rod E attached to their other ends and the lever F, which works in the frame G. The lever F is not attached directly to the rod E, but is fastened, at its lower end, to the springs H H on each side of it—these springs being fastened at the other ends to the rod E. By this arrangement the switch can be moved by a certain amount of pressure, sufficient to overcome the stiffness of the springs, although the lever F should be hitched. On the opposite side of the track from the switch is placed a guide, I, which guides the wheels of the branch train as it passes the connection.

For further illustration, we will suppose a train to be coming down on the main track, in the direction indicated by the black arrow, and also that the switch is in the position shown by the red lines, which is the proper arrangement for the trains on the branch passing either way. In this case the wheels on the outside rail A continue steadily on, while the corresponding wheels on the other side press against the rail C of the switch, forcing it into the proper position until the train passes, when the reaction of the springs H H' draws it back in its first position. Again, we will suppose a train coming down on the branch road, in the same direction, and that the switch is in the position shown by the drawing, that is, set for the main track: in such an instance the outside wheels, coming between the outside rail B and the guide I, are directed upon the main rail A, while the corresponding wheels on the other side press against the rail C of the switch, pushing the latter in the position shown by the red lines, which is the proper one for that train, and the springs H H' reacting as before. Thus it will be seen that trains coming in either of the two directions mentioned rectify the position of the switch, should it be wrong. But trains going in an opposite course are directed as the switch may be set, without altering its position; but in no instance is the train thrown off the track, as is frequently the case with the ordinary switch; and by means of my invention I secure safety upon a point which is so often the explanation of serious accidents.

I am aware that switches have heretofore been moved by means of some attachment to the locomotive, aside from the parts ordinarily used, and do not claim that as my invention; nor do I claim a spring-rail, not a part of the switch; but what I do claim as my invention, and desire to secure by Letters Patent, is—

A railroad switch so constructed and arranged that, if left in a wrong position, the wheels of the passing train will return the rails temporarily to their proper position, and the train continue upon the main track, substantially as herein set forth.

BENJ. F. FARRAR.
